UNITED STATES PATENT OFFICE.

JAMES H. MATTHEWS, OF PITTSBURG, PENNSYLVANIA.

FORM FOR CYLINDER-PRESSES.

No. 823,062.

Specification of Letters Patent.

Patented June 12, 1906.

Application filed September 1, 1905. Serial No. 276 718.

To all whom it may concern:

Be it known that I, JAMES H. MATTHEWS, a citizen of the United States, residing at Pittsburgh, in the county of Allegheny and State of Pennsylvania, have invented certain new and useful Improvements in Forms for Cylinder Printing-Presses, of which the following is a specification.

My invention relates to improved forms for use in connection with cylinder printing-presses. These forms are arranged to receive and hold in place movable type by means of movable spacing-strips, and said strips and the type secured thereby are locked in place by the resiliency of the material of the form. Novel means for accomplishing these ends in view are shown.

The object of my invention is to provide a convenient form upon which the letters or type may be set up and held in place and in which substitutions of letters or type's may be readily made without disturbing the remainder of the composition and which may as a unit be attached to the press and in so 25 attaching automatically bind the type in place to prevent displacement.

In the accompanying drawings, which make part of this application; Figure 1 is an end view of my improved form. Fig. 2 is a 30 plan view of the same. Fig. 3 is a section along the line 3 3 in Fig. 2. Fig. 4 is a section along the line 4 4 in Fig. 2, and Fig. 5 is a section along the line 5 5 in Fig. 2.

The following is a detailed description of the drawings: 1 is the form-base, being a sheet of metal, preferably resilient and bent to conform with the curvature of the press-cylinder to which it is to be attached. 2 is a metal strip attached transversely to said 35 base and provided with an integral flange 6. Adjacent to the opposite end of said base are attached thereto a pair of complementary beveled strips 7 7, forming a guideway, in which are seated the blocks 8 8, a block for every movable spacing-strip, as will be explained.

9 9 are holding plates or cleats which are attached to blocks 8 8 by screws 10 10. It is evident that by driving in screws 10 10 the 45 cleats 9 9 are readily fixed rigidly in any desired position.

11 11 represent parallel binding-strips attached to the curved edges of base 1 by means of screws 12 12, the blocks 13 13 serving to space said strips a sufficient distance 55 away from the base 1 to allow the flanges of

the type to slip under the said strips. The holes in strips 11 11 for the screws 12 12 are slotted slightly longitudinally to provide freedom of movement for said strips when 60 the base is sprung out of its normal curvature.

14 14 represent one or more movable strips or spacers. One end of each of said movable strips is inserted in the recess 16, formed by 65 flange 6 of the strip 2. The ends of said strips 14 14 are upset or turned in to form a bearing-surface which abuts against the strips 17 17, attached to base 1. It is evident that the left-hand ends of said strips, as 70 shown in Figs. 1 and 2, are held in place by flange 6 and strip 17. The other extremities 15 15 of said strips 14 14 are pressed into place to bear against the corresponding strip 17. A spacing-block 8 is now moved along 75 until its cleat 9 rests upon the end 15 of the strip 14. The strips are thus placed in their desired locations, and the form is ready for setting the type.

The type or letters 18 18 have curved impression-faces to correspond to the arc of the cylinder of the press and are provided at their bases with lateral flanges 19 19 to enter under the stationary strips 11 11 or movable strips 14 14, which are held from contact 85 with the base of the form by the interposition of the strips 17 17, as shown. When the desired type have been placed between the strips in the arrangement required, the movable strips are shifted until the type are held 90 snugly between them and the strips 11 11, as the case may be. The screws 10 10 are now tightened and the cleats 9 9 forced down until the strips 14 14 are held against slipping. Previous to assembling the type and 95 adjusting the movable binding-strips the plate or base 1 is flexed into a position such as shown in Fig. 1 in dotted lines by placing said base-plate on a block or rest known as a "spreader-block." When the type are assembled and the strips 14 14 properly adjusted, the spreader-block is removed, and the base 1 springs back into its normally-curved form, thus binding the type and binding-strips firmly in position. It is evident 105 that the type cannot escape from the form while in use on the press or at any time when sprung into its normal curvature.

Many variations of the means shown for securing the ends of the strips 14 14 previous 110 to allowing the plate 1 to spring back to its normal curvature will present themselves to

one skilled in the art; but my invention contemplates any means convenient for that purpose and is not limited to the exact construction shown.

5 What I claim as novel is—

1. In a form for cylinder printing-presses, the combination of a curved base-plate of spring metal, type having flanges on their bases, fixed edges on said base-plate adapted to engage said flanges, adjustable spacing-strips adapted to engage said flanges and to aline and lock said type when said base-plate is bent out of its normal shape and means when said base-plate springs back into its normal shape for securing the ends of said spacing-strips.
2. In a form for cylinder printing-presses, the combination with a curved base-plate of spring metal and flanged type, of movable locking-strips adapted to secure said type in place when said base-plate is bent out of its normal shape and means for securing the ends of said strips.
3. In a device of the class described, the combination with flanged type, of a curved resilient plate having fixed edge strips adapted to engage one flange of said type, locking-
- strips to aline and lock said type in place when tension is applied by the resiliency of said plate, means for retaining the ends of said locking-strips and auxiliary means for locking said strips before said tension is applied.
4. In a form for cylinder printing-presses, a curved base-plate, an adjustable spacing-strip, a flanged strip fixed to said base-plate and adapted to engage one end of said spacing-strip, a second fixed strip adapted to hold the end of said spacing-strip in said engagement, a pair of complementary beveled strips fixed to the opposite end of said base-plate, a strip fixed to said base-plate parallel with said complementary strips and means carried by said complementary strips for clamping the other end of said adjustable strip against said last-mentioned fixed strip, substantially as described.

In testimony whereof I have affixed my signature in presence of two witnesses.

JAMES H. MATTHEWS.
